UNITED STATES PATENT OFFICE.

FLOYD C. FURLOW, OF MONTCLAIR, NEW JERSEY, ASSIGNOR TO OTIS ELEVATOR COMPANY, OF JERSEY CITY, NEW JERSEY, A CORPORATION OF NEW JERSEY.

FLUID-DASH-POT BUFFER DEVICE.

986,378.

Specification of Letters Patent. Patented Mar. 7, 1911.

Application filed October 9, 1907. Serial No. 396,553.

To all whom it may concern:

Be it known that I, FLOYD C. FURLOW, a citizen of the United States, residing in Montclair, in the county of Essex and State 5 of New Jersey, have invented a new and useful Improvement in Fluid-Dash-Pot Buffer Devices, of which the following is a specification.

My invention relates to safety buffers for 10 elevators, and one of its objects is the provision of simple and efficient means for gradually retarding an elevator car independently of its operating apparatus so as to bring the car to rest gradually with mini- 15 mum shock or jar.

A further object of the invention is the provision of means for resetting or returning 20 to its initial position the buffer device upon the release therefrom of the moving part of the elevator which is arranged to be brought into engagement with a moving part of the buffer device.

Other objects of the invention will appear 25 hereinafter, the novel combinations of elements being set forth in the appended claims.

In the accompanying drawings, Figure 1 represents an elevator system illustrating the application of my invention; Fig. 2 is a vertical sectional elevation of one form of 30 my improved buffer device including the resetting means therefor; and Fig. 3 is a view similar to Fig. 2, but showing a modification.

In general, my invention comprises a 35 buffer device or shock absorber to overcome the inertia of a moving body in an elevator in gradually stopping the same. In the drawing I have shown the buffer device at the lower limit of travel of an elevator car, 40 although obviously it may be placed in the path of the counter-weight or in the path of any other moving part which it is desired to stop gradually, whether such part is in an elevator system or other analogous apparatus.

In Fig. 1 two cushioning devices of the form shown in detail in Fig. 3 are shown at the lower limit of the elevator well so as to be engaged by the elevator car as the same 50 approaches its lower limit of travel, and by the combined retarding action of springs and a varying fluid pressure, bring the car to a complete stop gradually and independently of manual controllers, although the

car may be descending at a high rate of 55 speed.

Fig. 1 illustrates a typical hydraulic elevator of the well known plunger type, the elevator car 1 traveling along the usual guide-rails (not shown). To the bottom of 60 the car is securely attached the plunger 2 which is arranged to move up and down freely in the main cylinder 18. The latter is supplied with fluid under pressure through the to-and-fro pipe 16 from the pressure 65 supply pipe 14 through the change valve 17. 15 designates the discharge or exhaust pipe.

The operation of the change valve 17 is controlled by means of a hand lever 10 in 70 the car coöperating with the standing ropes 9, the sheave 11, the pinion 12 and the rack bar 13 in the well known manner. The standing ropes 9 are fastened at 8 to the overhead beam 6. The cable 4 is attached 75 to the upper side of the car and extends upwardly over the sheave 5, mounted on the overhead beam 6, to the counterbalance weight 7. The counterweight partially balances the combined weight of the car and 80 plunger. The cylinder 18 is closed at its lower end by a head 19 and when the car operating lever 10 is moved in one direction or the other, the change valve 17 will be operated to open or closed position to allow 85 the supply pressure to act on the plunger to lift the car, or so as to cause the unbalanced weight of the car and plunger and load to force the fluid out of the cylinder through the exhaust pipe 15. 90

Although in some instances only one buffer device would be sufficient, it would be preferable in stopping an elevator car to employ a plurality of them. In this instance I have shown two buffer devices 20 in Fig. 1 95 at the lower limit of travel of the elevator car, and so placed in respect thereto that each will be engaged by the bottom of the car near the lower limit of the car's travel.

Referring now to Fig. 2 which shows the 100 details of one form of my invention, 21 designates a heavy compression spring loosely supported in a tube 22, and extending a short distance above the latter. The lower end of this tube is connected by the coupling 105 23 to the upper end of the tube 25. This coupling is screw-threaded at its ends to fit into the screw-threaded lower end of the tube 22.

and the screw-threaded upper end of the tube 25, the middle portion of said coupling being of substantially the same diameter as the tubes. The lower end of the tube 25 is 5 screw-threaded into the piston 26 which fits closely in the cylinder 31, and which is provided with circumferential grooves 27. The tubes 22 and 25 with the coupling 23 form a piston rod for the piston 26. The lower end 10 of the cylinder 31 is screw-threaded in a flange 32 formed integral with a standard or support 33 which forms a closed bottom for the cylinder 31 and also supports it in an upright position.

15 Surrounding the cylinder 31 and the tube 25 is an outer cylinder casing 34, the lower end of which fits over the flange 32 and is provided with external screw threads to receive an internally threaded ring 35, secured 20 to the support 33 by bolts 36. The upper end of the casing 34 is provided with a head 37 which is firmly secured in position by means of a ring 38 which is screw-threaded onto the upper end of the casing 34. The 25 head 37 and the ring 38 are secured together by bolts 39. The head of the casing is provided with a central opening through which the tube 25 can slide freely, but without any lateral play, so that the tube 25 is guided 30 in its vertical movements, and the piston head 26 prevented from binding in the cylinder 31.

Within the cylinder 34 is a series of helical springs 40 placed one above another and 35 separated by rings 41. Above the uppermost spring 40 is placed a disk or washer 42 which bears against said spring. Above the disk 42 is a ring or stop-collar 43 secured to the tube 25 by screws 44. This ring forms 40 a stop or abutment for the disk 42, and also forms a stop to limit the upward movement of the tube 25 in the casing 34. The compression springs 40 serve to hold the tube 25 and parts carried thereby in their upper 45 most position as shown in the drawing, and in this position the springs 40 are preferably slightly compressed. When the buffer device is operated and the tube 25 carried downwardly, the springs are compressed between the disk 42 which is carried down with 50 the tube, and the flange 32 on which the bottom spring 40 rests. The head 37 of the casing and the disk 42 are provided with openings 45 for the passage of air to and from the casing as the tube 25 moves up and down.

The cylinder 31 is provided with large openings 47 near its top, and below said openings is a spirally arranged series of 60 small holes 48. It will be observed that the openings 47 are comparatively large and the pitch of the spiral row of holes is greatest near the top of the cylinder, and gradually diminishes toward the bottom of the cylinder; also, that the distance between succes-

sive openings is gradually diminished from the top to the bottom of the row. With this arrangement the vertical distance between successive openings is gradually diminished from the top to the bottom of the cylinder. 70 The purpose of this arrangement will appear more fully hereinafter. Obviously the same result might be attained by making the spiral row of openings of uniform pitch throughout, and making the distance between adjacent openings greater near the top and less near the bottom. Or, the same result could be obtained by making the distance between adjacent openings uniform throughout, and varying the pitch to a 75 greater extent than is shown on the drawings. Other arrangements of the openings might be adopted which would accomplish the same results.

The tube 31 and cylinder 34 are filled with 85 some suitable liquid, such as water or oil, up to the top of the cylinder 31 or higher. While it may be feasible to use water or other liquid or even to have the cylinder contain only air, I prefer to employ oil, 90 since it prevents rusting or corrosion, does not evaporate appreciably, and at the same time lubricates all the moving parts. Furthermore, there is no possibility of the oil freezing and thereby rendering the device 95 inoperative.

The operation of the buffer device is as follows. As soon as the elevator car or other moving part desired to be stopped gradually, strikes the spring 21, the same is compressed 100 and the tube 25 and the piston 26 started gradually downwardly. The spring 21 acts as a cushion for the tube or actuating device 25 and piston 26, and thus prevents them from receiving a sudden blow, and permits 105 them to be started up gradually. The oil contained in the cylinder 31 is now forced to flow through the openings 47 and 48. During the initial movement the large openings 47 permit a free escape of the oil and the piston is restricted but little in its movement, and the retarding effect on the elevator is due principally to the inertia which has to be overcome in quickly starting the moving parts of the buffer device. As the lower end of the piston 26 passes below the 110 openings 47, the escape of the oil is confined to the small openings 48, and the flow of oil from the cylinder is retarded. As the piston 26 continues to move downwardly, the retardation to the flow of oil gradually increases by reason of the gradually decreasing number of openings 48 below the piston. The rate at which this retardation increases 115 also increases as the piston moves downwardly, owing to the gradually diminishing vertical distance between the openings. In other words, the lower the piston is in the cylinder, the more openings 48 will be covered in a given length of travel of the 120 125 130

piston. When the piston 26 has covered the lowest opening 48, any further downward movement of the piston is prevented, since the oil under the piston has no outlet and the nature of the fluid does not permit of compression since it is substantially non-
elastic.

It will be seen that the buffer device will effectually operate to quickly and smoothly bring the elevator car to rest. The higher the speed of the car, the more powerful will be the reacting retarding effect. It is a well known physical law that the resistance to the escape of a liquid through a restricted opening is substantially proportional to the square of the speed with which it escapes. It is also well known that the power necessary to overcome the momentum of a moving body in bringing it to rest within a certain length of travel is proportional to the square of its velocity. It follows from the application of these laws to the operation of the buffer device that the retarding effect of the openings 47 and of the restricted openings 48 will be directly proportional to the square of the speed of the piston 26 and therefore directly proportional to the power necessary to overcome the momentum of the moving parts in bringing them to rest during the travel of the piston through the cylinder 31. As a practical example, to make the application of these laws clear, let it be assumed that the piston is moving downwardly with a velocity of 20 feet per second, that its lower end is just above the large openings 47, that the weight of the moving parts is such that an upward force of 500 pounds on the piston is necessary to bring the parts to rest by the time the piston has reached its lower limit of travel, and that the size of the openings is such that a downward pressure of 500 pounds on the piston will be necessary to overcome the retarding effect of the openings when the piston is moving with a velocity of 20 feet per second. Then the upward pressure of the oil on the piston is 500 pounds, the amount needed to reduce its speed at the proper rate to bring it to rest at the bottom of the cylinder. Comparing with this an example in which the speed of the piston is doubled, or 40 feet per second, with the parts in the same position, it will be seen that the upward pressure necessary to bring the parts to rest by the time the piston reaches its lower limit will now be quadrupled, or 2,000 pounds. But the retarding effect of the oil which is now being forced through the openings 48 with double the velocity will also be quadrupled, or 2,000 pounds. It will thus be seen that the retarding effect of the oil for any given speed of the piston will always be proportional to the power needed to overcome the momentum of the moving parts within a given length of travel. By mak-

ing the openings of the proper size for one speed, they will operate equally well for any other speed, and the great advantage of this over springs and other devices which are effective only within narrow limits of speed, is obvious. By the use of oil or other liquid the tendency of the elevator to rebound is also entirely removed.

It has been found in practice preferable to arrange enlarged openings 47 at the top and the openings 48 in a spiral series with the vertical distance between adjacent openings near the top of the cylinder greater than that between the openings near the bottom. By this arrangement the openings 48 are cut off by the piston at a more nearly uniform rate than if they were uniformly spaced, owing to the gradually decreasing speed of the piston as it descends. In other words, the arrangement is such that the retarding influence of the escaping oil is substantially constant throughout the travel of the piston 26, but proportional to the momentum of the moving body to be gradually stopped. When such body first strikes the buffer device the flow of the oil should be comparatively free, but the resistance to movement or the pressure produced on the oil the same as when the momentum is being subsequently overcome. That is, the back pressure of the oil in overcoming the momentum is substantially constant throughout the travel of the piston 26.

As soon as the elevator car or the moving part which has engaged the spring 21, is moved away from the buffer device, the piston and attached mechanism is forced upwardly by the springs 40 to reset or restore the moving parts to their normal or original positions as shown in the drawings, the stop-collar 43 being then in positive engagement with the head 37 of the casing 41, to prevent the piston head 26 being carried above the cylinder 31, the springs 40 being still slightly under compression. As the piston moves upwardly the oil flows back into the cylinder and the buffer device is again ready for operation.

Referring now to Fig. 3 which shows a somewhat modified construction, the compression spring 21' is surmounted by a rubber cushion 50 which helps to deaden the blow of the elevator car or other moving part when it strikes the buffer. The spring 21' is loosely mounted in a short tube or inverted cap 22' secured to the top of a tubular piston rod 25'. The lower end of the piston rod 25' is screw-threaded to receive a collar 51 bolted onto a piston 42'. The piston rod is provided with a series of perforations 52 near its lower end. A tubular casing 34' similar to the casing 34, is screw-threaded into a support or standard 33' which is provided with holes for bolts or other fastening means to securely hold the buffer device in proper

position. The bottom of the casing 34' is provided with a central recess 54 which is screw-threaded to receive the lower screw-threaded end of the tube 55. Within the tube 55 is a hollow rod 56 extending from the bottom of the tube 55 up through a central opening in the piston 42' and into the piston rod 25'. Surrounding the rod 56 is a coil spring 57 which rests on the tube 55 and forms a resilient stop for the piston 42' and parts carried thereby. The hollow rod 56 is provided with a series of graduated openings 58 extending from near the top of the rod to a point a short distance 15 above the top of the tube 55. These openings are gradually diminishing diameters from the top one, which is large enough to offer little resistance to the flow of oil therethrough, to the lowest opening which 20 will allow the oil to pass only very slowly. A coil spring 40' yieldingly holds the piston 42' in its upper position and returns it to such position after the buffer device has operated. Bolted to the upper end of the casing 34' is a hollow cap 60, which forms a liquid receptacle. This cap surrounds the hollow piston rod 25' and is provided with a stuffing box 61 to guide the tube 25' and prevent escape of the liquid. The receptacle 25 taken as a whole and including the cylinder 34' and cap 60 is filled with oil or other liquid. The hollow rod 56 is therefore also filled. The operation is similar to that of the construction shown in Fig. 2. When 30 the piston commences its downward movement, the oil beneath it will be forced into the hollow rod 56, the oil already in the rod being forced out through the top of the rod or the openings 58 which are above the piston, and through the openings 52 into the 35 space above the piston. This circulation of the oil continues as the piston descends, the restriction to the flow of oil gradually becoming greater as the number and size of the openings 58 below the piston diminish. When the piston has covered the last opening 40 58, it will be brought to rest, owing to the incompressible nature of the oil, unless there is leakage between the piston 42' and the cylinder 34', or between the piston and the rod 56, in which case it may move far enough to compress the spring 57, and will then be brought to an absolute stop. The spring 57 will act as a buffer to stop the car 55 without any jar in case it is not brought to a complete stop by the retarding effect of the oil.

While I have described my device in connection with an elevator system, there are 60 doubtless other uses to which my invention could be put to great advantage without invention. I have shown different forms of construction embodying my invention, but it might be embodied in various other 65 forms, and it is obvious that various changes

in details and arrangement of parts might be made by those skilled in the art without departing from the spirit and scope of the invention. I, therefore, desire not to be limited to the precise constructions and arrangements of parts disclosed. 70

What I claim as new and desire to secure by Letters Patent of the United States is:—

1. In an elevator buffer, the combination with a receptacle, of a tubular member within the receptacle provided with a series of perforations, and a piston having sliding contact with said member, and substantially unobstructed during its initial movement. 75
2. In an elevator buffer, the combination with a receptacle, of a cylinder provided with perforations communicating with the interior of the receptacle, and a piston having sliding contact with said member and movable past said perforations successively, 80 said perforations being positioned to permit a rapid acceleration of said piston from its initial position. 85
3. In an elevator buffer, the combination with a receptacle for containing a liquid, of a hollow member within the receptacle open at one end to atmospheric pressure and provided with a series of lateral openings, and a movable member provided with means for forcing a liquid through said lateral openings, and gradually reducing the number of openings through which the liquid may pass. 90
4. In an elevator buffer, the combination with a receptacle for containing a liquid, of a tube within the receptacle open at one end and also provided with a series of lateral openings, and a piston within the receptacle having close sliding engagement with the tube. 100
5. In an elevator buffer, the combination with a receptacle for containing liquid, of a cylinder within the receptacle formed with a series of lateral openings, and a piston in sliding engagement with the cylinder, the 110 said parts being arranged to permit a free flow of the liquid from in front of the piston during its initial inward movement. 105
6. In an elevator buffer, the combination with a receptacle for containing liquid, of a cylinder within the receptacle open at one end and also formed with lateral openings near said end of a size to permit a free passage of the liquid, and a series of smaller openings between said first openings and the 120 other end of the cylinder, and a piston movable in engagement with the cylinder. 115
7. In an elevator buffer, the combination of a receptacle for containing liquid, a cylinder within the receptacle formed with lateral openings, and a piston in slidible engagement with the cylinder, the liquid on opposite sides of said piston having unobstructed communication during the initial 125 inward travel of the piston. 130

8. In an elevator buffer, the combination with a receptacle, of a tube within the receptacle open at one end and formed with a series of lateral openings at successively diminishing distances apart as measured longitudinally of the tube and from said end, and a piston in sliding engagement with the tube. 5
9. In an elevator buffer, the combination with a receptacle for containing liquid, of a tube within the receptacle open at one end and formed with graduated lateral openings, and a piston in slidable engagement with the tube and unobstructed during its initial inward movement. 10
10. In an elevator buffer, the combination with a receptacle for containing a liquid, of a tube within the receptacle open at one end and formed with a lateral opening or openings permitting a restricted flow of the liquid between the tube and receptacle, a cap or cover for the receptacle, a piston rod slidable through an opening in said cover, and a piston head carried by the rod 20 and in slidable engagement with the tube. 25
11. In an elevator buffer, the combination with a fluid dash-pot comprising a cylinder and a piston, of an actuating device connected to said piston and extending 30 out of the cylinder, a resilient buffer member mounted on said actuating device, and a stop or abutment on said actuating device, and means engaging said stop for holding said piston normally in a predetermined position and for automatically resetting the same after being actuated and released. 35
12. In an elevator buffer, the combination with a fluid buffer dash-pot comprising a piston and piston rod, of a plurality of springs arranged in series, and a connection between one of the springs and the dash-pot piston rod to effect a restoration of the piston to normal position by the action 40 of said springs. 45
13. In an elevator buffer, the combination with a hollow member open at the top, laterally perforated and closed at the bottom, of a piston movable in said hollow member, 50 an actuating rod connected to said piston, and a spring for restoring said piston to initial position and holding it there while no pressure is exerted on said actuating rod, the latter engaging said spring. 55
14. In an elevator buffer, the combination with a closed receptacle, of a tube within said receptacle and rigidly connected thereto, said inner tube having lateral perforations and being entirely closed at and near the bottom and open at the top, a piston movable within said inner tube, a piston rod, and a spring within said receptacle for holding said piston and piston rod in initial position. 60
15. In an elevator buffer, the combination with a receptacle, of a tube within the receptacle, a piston slidable in said tube, a piston rod, and a spring interposed between the tube and receptacle and acting on said piston rod. 65
16. In an elevator buffer device, the combination with a hollow member open at the top, laterally perforated and closed at the bottom, of a piston movable in said hollow member, an actuating rod connected 70 to said piston, and a spring for returning said piston to initial position and holding it there while no pressure is exerted on said actuating rod, the said spring being located outside of said hollow member. 75
17. In an elevator buffer device, the combination of a closed receptacle, a tube within said receptacle and rigidly connected thereto, said inner tube having lateral perforations and being entirely closed at and near the bottom and open at its upper end, a piston movable within said inner tube, a piston rod, and a spring within said receptacle for holding said piston and piston rod in initial position, said spring being 80 located outside of and surrounding said inner tube. 85
- In testimony whereof, I have signed my name to this specification in the presence of two subscribing witnesses.
